UNITED STATES PATENT OFFICE.

PHILIP D. PARSONS, OF PHILADELPHIA, PENNSYLVANIA, ASSIGNOR, BY MESNE ASSIGNMENTS, TO SCOTT PAPER COMPANY, A CORPORATION OF PENNSYLVANIA.

MACHINE FOR APPLYING LABELS TO PAPER ROLLS, ETC.

Application filed October 3, 1922. Serial No. 592,034.

To all whom it may concern:

Be it known that I, PHILIP D. PARSONS, a citizen of the United States, and resident of Philadelphia, county of Philadelphia, and State of Pennsylvania, have invented an Improvement in Machines for Applying Labels to Paper Rolls, Etc., of which the following is a specification.

This invention is more specifically intended for automatically applying label bands about rolls of toilet or other paper, in an efficient and perfect manner, the same being accomplished more rapidly, more accurately as to positioning, and with cleaner results than has been possible by hand operation.

While my invention is particularly intended to employ bands which are also labels, I do not restrict myself to the employment of bands of this character; and while the invention is intended for banding toilet paper rolls, it may be employed in connection with the banding of any other materials in predetermined shape, such as canned or cartoned goods.

With the above and other objects in view, the nature of which will be more fully understood from the description hereinafter, the invention consists in the novel construction of machine for applying labels to paper rolls, etc., as hereinafter more fully described and defined in the claims.

Referring to the drawings: Fig. 1 is a plan view of my improved machine for banding paper rolls; Fig. 2 is a front elevation of the same; Fig. 3 is a side elevation of the same; Fig. 4 is a horizontal sectional view of the main portion of the machine, taken on line 4—4 of Fig. 2; Fig. 5 is a perspective view of a portion of a label or band feeding mechanism; Figs. 6 to 12, inclusive, are horizontal sectional views corresponding to Fig. 4 showing the several steps performed by the machine in applying the band or label; Fig. 13 is an elevation of a portion of the machine shown in Fig. 3 on a larger scale; Fig. 14 is a sectional view of a detail; and Fig. 15 is a horizontal section showing the means for actuating the folders.

2 is the main frame of the machine and supports the table 71. At the front portion of the table 71 and extending laterally

to the left is a conveyer frame 3 having a guide floor 4 over which the rolls of paper R are moved by the action of endless traveling chains 5, 5, constituting a conveyer; the 55 rolls R being guided between longitudinal side guides 6 of angle iron. The chains 5, 5, are driven by a pulley 74^b (Fig. 2) which is rotated by a band or belt 75, in turn moved by a grooved driving wheel 76 secured to a 60 power shaft 52. The shaft 52 is driven by chain and sprocket wheels 53, which receive motion from a power pulley 54 driven by an electric motor 55. The shaft 52 may be driven in any other manner, if so desired. 65 When the paper roll R leaves the custody of the chains 5, 5, it is transferred to the supporting and feed rollers 7, which are driven by an endless chain 8 from the operating means for imparting movement of the chains 70 5, 5, (Fig. 4). In this manner, the paper roll R is fed forward until it comes to rest in contact with the abutment plate 9 (Figs. 1 and 2), from which position the roll is then fed at right angles against the paper band or 75 label wrapper L (Fig. 6), the feeding being accomplished by a reciprocating pusher head 10 (Figs. 1 and 4). The pusher head 10 is secured to the end of a rod 56 guided in bearings 57 under the table 71 and is reciprocated by a lever 58 hinged to the main frame 2 and oscillated by link 59 and crank 60, said crank secured to a shaft 49 provided with a gear wheel 50 and driven by a pinion 51 secured to the power shaft 52 (Figs. 2 and 3). 80 When the pusher head 10 advances, it moves the paper roll through the successive positions shown in Figs. 6, 7 and 8 and into the custody of the wrapping arms 74, this being the limit of the pushing action, as will be 85 understood by reference to Figs. 3 and 4.

As the rolls R are being continuously moved or tended to be moved along the conveyer to a position in front of the pusher 10, it is necessary to provide means for holding 90 back the rolls until the pusher is in outward position to receive a roll. To accomplish this, I provide a spring actuated finger 11 which is forced normally into the position shown in Figs. 1 and 4 by spring 13. The 100 pusher 10 is provided with an automatic trip 14 which, when the pusher is moving out-

- ward, causes the finger 11 to be withdrawn to permit one of the rolls R to be fed to the position in front of the pusher; but the trip releases the finger just before the pusher re-
 5 cedes to its outermost position, so as to permit the finger to be forced back to position shown to hold back all of the other rolls. This finger is caused to be reciprocated with each reciprocation of the pusher.
- 10 The trip finger 14 is hinged to a lateral extension from the pusher 10 and is held at right angles to the direction of movement of the pusher and the retaining finger 11 by a spring shown at 14^a in Fig. 1. As
 15 the pusher is being withdrawn to permit a roll to pass in front of it, the trip finger 14 will be brought into contact with the block 12 on the retaining finger 11 and the spring 14^a being sufficiently strong will retain the
 20 trip finger in the position shown so that its backward movement with the pusher 10 will move the block 12 and the retaining finger 11 backward against the tension of the spring 13, said spring being supported
 25 at its outer end by the frame 13^a in which the retaining finger is guided. This action moves the finger back sufficiently to allow one of the rolls of paper to be moved past it into position in alignment with the pusher.
- 30 At this time the pusher is still moving outward and as the retaining finger cannot move outward further, the resistance of the block 12 is such that the trip finger 14 will be oscillated against the action of the spring
 35 14^a and its end will slide over the rearwardly extending plate 12^a on the block 12 and ultimately snap over the outer end thereof, freeing the retaining finger 11 so that it is moved forward under the action of its spring
 40 13 immediately back of the roll which has passed beyond it. When the pusher reverses its movement and advances to push the roll of paper forward against the label and wrapping device, the trip finger 14 will strike
 45 the plate 12^a and as said plate and its block 12 are held against forward movement by the frame 13^a, Fig. 1, the finger will again be oscillated as it slides over the said plate 12^a and once more assumes the position as
 50 shown. In this manner, the trip finger may oscillate in either direction according to the resistance encountered but the tension of its spring 14^a is always sufficient to enable the trip finger to overcome the spring 13
 55 of the retaining finger.
- Referring now to the means for feeding a band or label L into position to receive the roll R (Fig. 6), it will be seen that above the table 71 there is a magazine floor 15
 60 having its forward end provided with a chute 23 down which the label L is fed to a position in front of the advancing roll in the custody of the pusher. This chute 23 is open in its middle and lower portion
 65 to expose the middle portion of the label

and permit the passage of the roll and pusher head (Fig. 4). When the roll R is moved against the label L (Fig. 6) and assumes the successive positions (Figs. 7 and 8), the ends l, l', of the band or label are drawn out of the chute pockets and one of said ends, namely l, when liberated, springs against a paste rod 66 and receives paste wherewith to seal the overlapping ends, as insured by the operations shown in Figs. 10, 75 11 and 12. In this connection, it will be seen that the right hand pocket of the chute is provided with an adjustable guide plate 72 clamped in position of adjustment by screw clamp 73 and adapted to control the time of releasing the end l of the band to insure its liberation accurately with the timing of the paste applying rod 66, whereby the latter is fully raised when the said end l is released and for the further object of 85 determinating the amount of paste or glue deposited upon the label. The longer the release of the end l is delayed, the less will be the amount of paste or glue deposited. In receiving the paste or glue, the label end 90 l wipes against the paste applying rod 66, and to definitely locate the paste or glue, I provide the rod 66 with a plurality of projections 68 (Fig. 13), which are the places of contact and hence insure deposit of paste 95 or glue in three narrow and short bands on the flap or end l. The paste applying rod 66 is reciprocated vertically in the paste or glue pot 67 by an operating lifter rod 64 having a lateral connection 65 with the 100 paste applying rod 66 (Figs. 3 and 13). The vertical movement is imparted to the lifter rod 64 by a pivoted lever 62 having a hinged connection with the main frame 2 at one end and at the other end pressing 105 upwardly against a roller 63 on the lifter rod, the lever 62 being oscillated by link 61 connected at the top with the said lever and at the bottom with the crank 60 on shaft 49 before referred to (Figs. 2 and 110 3). This gives the proper timed reciprocation to the paste applying rod relatively to the reciprocations of the pusher head 10, so that the latter pushes the roll R against the label just as it is in position to take 115 the paste or glue from the rod 66.

Referring now to the means for feeding the labels or bands L to the chute 23: The labels are stacked in an upright position against a rear support 16 (Figs. 3 and 5) 120 which is secured to horizontal endless chains 18 driven slowly by a shaft 19 above the chute, the driving being accomplished by worm 37 and worm wheel 38, the latter secured to the shaft 19. The worm is secured to a shaft 33 journaled in a bearing 34 and provided with a ratchet wheel 35. A pawl 36 hinged to a frame 31 pivoted on the shaft 33, operates the ratchet with a step by step motion. A spring 32 pulls the 125 130

frame 31 and pawl 36 in one direction and a rocking cam frame 30 pushes the frame 31 and its pawl in the other direction against the action of the spring. This frame 30 is oscillated by a vertical rod 29 hinged to it at 28; and said rod is reciprocated by an eccentric 48 on the end of the shaft 49, before referred to (Figs. 2 and 5). In this manner the stack of labels are moved very slowly forward toward the chute 23 and the forward upper plate 22 thereof. To give capacity for hand adjustment, I provide a friction clamp 39 between the shaft 19 and the worm wheel 38 and also a winged hub 40 on the end of the shaft. By turning the shaft 19 by hand, the chains 18 may be operated to move the support 16 forward or backward in order to insert a new stack of labels or to adjust the stack forward into operative position to initially cooperate with the suction feed arms 21.

20 is a hollow rock shaft journaled at each end in the side frames of the magazine floor 15. Extending laterally from this hollow rock shaft are a plurality of tubular suction arms 21, the open ends of which are in the same plane and adapted to press simultaneously in contact with the front sheet of the stack of labels L and by suction pull the label away from the others and move it forward above the chute 23. When the label reaches a position above the chute, the air suction is shut off, permitting the label to fall and this is insured by the plate 22 which acts as a stripper to the label as the suction arms pass forward beyond said plate. The floor of the magazine 15 is provided with supporting strips 17 (Fig. 1) of rubber or other material which presents frictional resistance to the edges of the stack of labels, with the result that when the suction arms 21 pull away the front label of the stack, the remaining labels retain their normal position. The hollow rock shaft 20 is provided with a gear wheel or segment 26 which meshes with gear or segment 27, the latter being secured to the oscillating cam frame 30 and is thereby oscillated by the means heretofore described for operating the cam frame 30. The suction is provided by a suction pump 24 with which the rock shaft 20 is connected by a flexible hose 25 (Fig. 5). The position of the suction pump is reciprocated by a crank 24^a, which is driven from shaft 49 by gears 49^a (Fig. 14). As the operation of the pusher head 10, the lifter rod 64 for the paste applying rod, the feeding means for advancing the labels, the rocking devices for the suction pipe 20 and the suction pump are all actuated from the same power shaft 49, it is manifest that all of these cooperating means and devices will be operated in timed relation.

As the feeding of the labels will take place automatically with each revolution of the

shaft 49, if not otherwise prevented, when there is no paper roll R passing through the machine, I provide an automatic controlling means which prevents the feeding of a label into the chute 23 whenever there is no paper roll R passing along the conveyer elements 4 and 5. This means comprises a relief valve 41 on the suction end of the suction pump and an operating rod 42, which when raised opens the valve and prevents the pump creating an operative suction through the pipe 20 and its suction arms 21. This rod 42 is hinged to a pivoted trip 43 which is hinged at 45 to the conveyer frame 3, said trip being counterweighted at 46, so that it projects above the floor 4 of the conveyer when no paper rolls R are holding it down. In this manner, when the rolls R are present, the rod 42 is held down and out of contact with the relief valve 41; but when no rolls are present on the conveyer, the counterweight 46 forces the trip and rod upward with the result that the relief is opened and suction prevented.

I will now describe the successive steps illustrated in Figs. 6 to 10, inclusive, which disclose the operations in encircling the paper roll with the band or label. As before explained, Fig. 6 shows the roll R moved by the pusher 10 into contact with the label L to be applied to it. Fig. 7 shows the same roll pushed further back and causing the label to be partly wrapped about the roll and the end l brought into contact with the paste applying rod 66, said label end having just passed from the custody of the plate 72 of the chute 23. Fig. 9 shows the paper roll and its label pushed still further back to the limit of the movement of the pusher head 10 and into the custody of the wrapping arms 74 which hold the label wrapped about the roll and with the free ends l, l', in position to be folded one over the other into pasted relation. The wrapping arms consist of two hinged arms 74 between which the paper roll passes, said arms curved toward each other at their forward ends and provided with small vertical rollers 74^a, said arms hinged at 75 to the rigid guide walls 70 secured to the floor 71 and spring pressed toward each other by the springs 76. Fig. 10 shows the folder 78 in action, as having just folded the unpasted end l' of the label down upon the roll. Fig. 11 shows the same general relation of the parts, but in this case the folder 78 is just receding while the other folder 84 is folding down the pasted end l of the label; and Fig. 12 shows the folder 78 fully receded and the folder 84 fully advanced to complete the folding down of the pasted end l of the wrapper. After this operation is completed the next roll is moved forward and pressed against the pasted overlapping ends l, l' and prevents said ends separating to produce a defective sealing.

As shown, the folder 78 consists of a pivoted finger hinged to the laterally reciprocating slide 77 and spring pressed toward the roll by a spring 80. Similarly, the folder 84 is hinged at 85 to a laterally reciprocating slide 83 and is spring pressed toward the roll by a spring 86, this last folder being provided with a pair of vertically rollers journaled in a pivoted truck 84^a to more perfectly roll down the pasted end *l* of the label. These folders 78 and 84 may be made in other forms if so desired, but should move successively so as to fold down the two ends of the label in succession.

The reciprocating plate 77 of folder 78 is secured to a reciprocating rod 81 which is spring pressed by spring 82 to force the folder 78 to the folding position shown in Fig. 10; and similarly the plate 83 of folder 84 is secured to a reciprocating rod 87 which is spring actuated by spring 88 to move the folder 84 from position shown in Fig. 10 to position shown in Fig. 12 or in a reverse direction to that given to folder 78 by its spring 82. The rod 81 is controlled by a bell-crank lever 89 and cam 90 movable with the pusher operating rod 56. Similarly the rod 87 is controlled by a bell-crank 91 and cam 92 also movable with the pusher rod 56.

It will be seen from Figs. 10, 11 and 12, that the folder 78 first advances to turn down the unpasted label end *l'* (Fig. 10), then the folder 84 moves forward from the opposite direction to turn down the other or pasted end *l* of the label while the folder 78 slightly recedes (Fig. 11), and finally the folder 78 is fully drawn back while folder 84 continues to advance and fully fold over and press down the pasted or glued end *l* upon the end *l'* (Fig. 12). Folder 84 remains in this position until the next paper roll R is pushed in by the pusher head 10, and then it is released and withdrawn; and the new roll to be banded with its label is pushed by the pusher between the spring actuated wrapping arms 74 and forces back the banded roll just completed, as will be understood by reference to Fig. 4. In this way, the succeeding rolls, which are fed in by the pusher, cause the banded rolls to progressively travel rearwardly through the guideway 69 formed between the side frames 70 and 70^a to the place of discharge for packing in the shipping cases. During this rearward travel, the rolls are in close contact and in this manner hold the pasted ends *l*, *l'*, of the wrappers in tight contact until the paste or glue is set.

Considering more specifically the operation of the devices which actuate the folders 78 and 84, it is manifest that they must each reciprocate once with every reciprocation of the pusher head 10 and its operating rod 56. The fact that the cams 90 and 92 are secured to and reciprocate with the rod

56, insures a timed operation of the bell-crank 89 and 91 and resulting reciprocation of the folders 78 and 84 which take place through the medium of the connecting mechanism comprising the spring controlled slide 81 for pusher 78 and spring controlled slide 87 for folder 84. In the position shown in Fig. 4, with the pusher head 10 fully in, the folders 87 and 84 are out as in Fig. 9. Then as the pusher head withdraws, the cam 90 in receding allows the slide 81 to be moved by its spring 82 to advance its folder 78. During this receding movement of the pusher, the bell-crank 91 and folder 84 are not actuated. But on the next forward movement of the pusher head and rod 56, the cam 90 operates bell-crank 89 to withdraw folder 78, and cam 92 operates the bell-crank 91 to advance the folder 84, as shown in Figs. 10, 11 and 12. This position of the folder 84 (Fig. 12) remains until the latter part of the advance of the pusher is being completed to force the new roll and band into the wrapping arms 74 (Fig. 9) and is then rapidly withdrawn, just in time to allow the new roll to be brought into contact with sealed band or label (Fig. 4).

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent is:—

1. A machine for applying and securing bands about articles, comprising a reciprocating pusher head by which the article to be wrapped is pushed, means for feeding a wrapping band in the path of the article, means for applying an adhesive to one end of the band, a pair of wrapping arms between which the article is pushed by the pusher head and by which the band is wrapped about the article, and folders in addition to and respectively arranged in position adjacent to the ends of the wrapping arms and adapted to relative movement transversely to the direction of the passage between said arms for folding the ends of the band held in wrapped position about the article one upon the other.

2. The invention according to claim 1, wherein further automatic means are provided for feeding the articles to be banded one at a time to the pusher head.

3. The invention according to claim 2,

wherein the automatic means consists of a continuous conveyer, and an intermittently acting control device actuated in synchronism with the backward movement of the 5 pusher head for regulating the delivery of the article to a time when the pusher head is back far enough to receive it.

4. The invention according to claim 3, wherein the intermittently acting control device comprises a spring actuated rod adapted to enter between the articles to be wrapped, and a spring actuated trip finger movable with the pusher head for causing the rod to be moved out of the path of 10 the articles momentarily to allow one of them to pass.

5. The invention according to claim 1, wherein the means for feeding the bands consists of a vertical guide chute open in 20 its middle for the passage of the article in contact with the band, means for supporting a plurality of bands above the chute, and suction devices having suction nozzles intermittently acting for transferring the 25 bands one at a time to the chute, and operating means for moving the suction nozzles in timed relation with the reciprocations of the pusher head.

6. The invention according to claim 5, wherein the suction devices comprise oscillating tubular suction arms, a pump for producing alternately a suction and pressure through the suction arms whereby suction 30 is provided when a band is being transferred to the chute and pressure provided when the band is to be released in passing into the chute.

7. The invention according to claim 6, wherein further a relief valve is provided 40 to prevent suction of the pump extending to the oscillating suction arm, together with automatic means arranged to be controlled by the articles to be banded whereby when no articles are present to be delivered to the 45 pusher head the relief valve is automatically opened.

8. The invention according to claim 7, wherein the automatic means comprises a counter-weighted oscillating arm over which 50 the articles to be banded are caused to travel, and a rod extending from the pivoted arm to the relief valve and actuated by the counter-weight when the arm is unrestrained by the presence of an article to be banded.

55 9. The invention according to claim 5, wherein further there is provided an upright support against which the bands rest, means for slowly feeding the support toward the chute, and means operating in synchronism 60 with the pusher head for feeding the support a distance approximating the thickness of the banding sheet with each reciprocation of the pusher head.

10. The invention according to claim 5, 65 wherein there are provided a plurality of

supporting friction strips upon which the bottom edges of the plurality of bands are supported to insure a retaining resistance against movement for all bands except the front one when it is being withdrawn by 70 the suction devices.

11. The invention according to claim 9, wherein the means for feeding the support comprise endless chains to which the support is secured, a shaft and sprocket 75 wheels for moving the chains in unison, an intermittently acting power means for giving to the shaft a very slow rotation.

12. The invention according to claim 11, wherein the power means comprise a 80 worm wheel on the shaft, a worm operating the worm wheel, a ratchet and pawl mechanism for intermittently rotating the worm, an oscillating cam frame for actuating the ratchet and pawl mechanism, and means for 85 operating the cam frame movable in synchronism with the reciprocating pusher head.

13. The invention according to claim 12, wherein further the oscillating cam frame 90 also operates the suction devices for intermittently bringing the suction nozzles, thereof into contact with the bands and then moving them to a position above the chute.

14. The invention according to claim 12, wherein further the shaft is frictionally held to the worm wheel and is provided with means whereby it may be manually rotated for quickly adjusting the support for the bands as when introducing a new packet of 100 bands or when adjusting the bands in operative relation to the suction nozzle.

15. The invention according to claim 1, wherein the means for applying the adhesive 105 consists of a pot for the adhesive, a rod movable vertically into and out of the pot and having a plurality of projecting portions for applying adhesive to parts only of the bands, and means for raising the rod with each 110 forward movement of the pusher head, the operation being such that the end of the band is caused to contact with the projections on the rod during the forward movement of article and band.

16. The invention according to claim 1, 115 wherein the means for feeding the bands consists of a vertical guide chute open in its middle for the passage of the article to be banded and providing side pockets for the ends of the band and from which they are 120 liberated when the article is pushed against the middle of the band, and wherein the means for applying the adhesive comprises a vertically reciprocating rod having a plurality of projections along its length, and 125 a pot for containing the adhesive into which the rod reciprocates the position of the rod being such that when the end of the band is withdrawn from the pocket of the chute and liberated, it will wipe against the pro- 130

6
jections on the rod and cause to be applied to its end portion a series of narrow layers of adhesive.

17. The invention according to claim 18,
5 wherein the pocket of the chute next to the adhesive pot and rod is provided with an adjustable plate presenting an edge from

which the end of its band is liberated, said plate adjustable to control the time of liberating the band and governing the length 10 of the pasted portions applied to the band.

In testimony of which invention I hereunto set my hand.

PHILIP D. PARSONS.
